UNITED STATES PATENT OFFICE.

JOSEPH E. WATTS, OF LAWRENCE, MASSACHUSETTS.

PRESSURE-REGULATOR.

SPECIFICATION forming part of Letters Patent No. 361,796, dated April 26, 1887.

Application filed March 19, 1887. Serial No. 231,479. (No model.)

To all whom it may concern:

Be it known that I, JOSEPH E. WATTS, a citizen of the United States, residing at Lawrence, in the county of Essex and State of Massachusetts, have invented certain new and useful Improvements in Pressure-Regulators; and I do hereby declare the following to be a full, clear, and exact description of the invention, such as will enable others skilled in the art to 5 ^{1c} which it appertains to make and use the same, reference being had to the accompanying drawings, and to letters or figures of reference marked thereon, which form a part of this specification.

15 This invention relates to "pressure-regulators," so called, by means of which the initial or live-steam pressure is reduced and regulated to suit the supply and requirements in other closed vessels or cylinders adapted for 20 purposes where very much less pressure of steam is needed.

My invention consists, primarily, in the general arrangement and method of operating the main valve, which is a "balanced" valve, so 25 ²⁵ called, whereby the movement of the latter is effected more gradually and the low-pressure system is not subjected to such extreme fluctuations as now occur where the main valve is not balanced, and is thus liable to extremes 30 of movement; secondly, in boring the main valve in such manner that the rear side of the valve, when the latter is closed, shall be subjected to the initial or high pressure in contradistinction to valves employed in regulators of this class, in which the rear side of the main valve is connected with and open to the low-pressure system when the said valve is 35 closed.

The drawings represent in Figure 1 a plan, 40 and Fig. 2 a central vertical section, of a pressure-regulator embodying my improvements.

The pressure-regulator shown in the accompanying drawings belongs to that class in which a weighted pulsating diaphragm operated by the variations in the low-pressure system serves to control a secondary valve, which in its turn regulates the movement of the main valve to admit or shut off steam under initial pressure, such opening and closing of the main 45 ⁴⁵ valve being accompanied by an increase or diminution of the pressure in the low system

to maintain the latter uniform and somewhat less than that of the said initial pressure.

A represents the exterior casing of the valve as an entirety, which is hollow and centrally provided with a "plunger-balanced" valve, B, so called, which reciprocates through the internal division-wall, a, and thereby controls the passage and regulates the supply between the inlet-passage C and the discharge D. The upper end of the main valve extends into a tubular cap, E, which incloses the actuating-spring b. Furthermore, said valve B is bored at e, as shown, by which a duct is formed leading to a closed chamber, F, normally open to and under the initial pressure. The lower part of the chamber F is furnished with a port, d, controlled by a secondary valve, G. The latter is connected by the valve-stem e with a pulsating diaphragm, H, which controls this secondary valve and forms the bottom of a hollow well, f, to be filled with water from the condensed steam, to prevent sudden jumping or resilient action of the diaphragm.

The reduction or difference in pressure between the initial supply and low-pressure system is effected by means of a weighted lever, g, and by the adjustment of the weights thereon the action of the diaphragm is controlled and regulated.

The principal object in my invention is to render the regulator more efficient, and this is accomplished by adjusting the several parts relatively to one another in such manner that the action of said parts shall be gradual; hence great fluctuations in the low-pressure system are avoided. Hence I have created two divisions, h i, and provided each with a small aperture, j, and by this means oblige the diaphragm to move slowly. The advantage of this is readily perceived upon operating the regulator. This operation is effected by premising that the entire system is inactive, in which event both valves B and G will be open. Upon the introduction of high-pressure steam its flow is unimpeded and it passes through the main supply C into the discharge D, which is interconnected with the independent pipe I at any suitable point. When the pressure in the low system is sufficient to exert a counter-force upon the diaphragm H, the latter is actuated and causes the secondary valve G to close. In

stantly therewith the pressure in the chamber F, then slightly less than the initial pressure, is restored upon the rear of the main valve and the latter is closed, moving against the 5 tension of the spring b, before mentioned. The main valve now remains closed and so continues until the pressure in the low system and that upon the diaphragm diminishes. The latter now pulsates upward, induced by the lever g, and the secondary valve is again slightly opened. This latter action reduces the pressure momentarily in the chamber F, and the main valve is free to open.

As soon as the live steam with its initial 5 pressure has again restored the low system to its normal, the main valve is again closed. Thus by balancing the main valve it is operated more easily and is more quickly controlled by the secondary valve. Furthermore, it is 10 always subjected, when closed or open, to the initial pressure which exists in the secondary chamber F in contradistinction to such regulators as have the secondary chamber directly connected and in free communication

with the low-pressure system at the time the 25 main valve is closed—a decided objection.

I claim—

1. In a pressure-regulator, the combination, with a balanced main valve having the duct c and the chamber F, connected with the said duct, by which said chamber is continually subject to the initial pressure, of the secondary valve G, controlled by the diaphragm and operating substantially as herein set forth.

2. In a pressure-regulating apparatus, the 35 combination of the main balanced valve B, the chamber F, constantly subjected to initial pressure by and through the main valve, and the pulsating diaphragm operating in the well-way f, the secondary valve G, which unites the 40 high and low pressure systems, and the independent pipe I, all substantially as specified.

In testimony whereof I affix my signature in presence of two witnesses.

JOSEPH E. WATTS.
